CONICAL BEAKER FOR DRAWING UP LABORATORY SAMPLES

Edwin G. Weichselbaum, St. Louis County, Mo., assignor
to Brunswick Corporation, Chicago, Ill., a corporation
of Delaware

Filed July 21, 1965, Ser. No. 86,234

Term of patent 7 years

(Cl. D16—1)

FIG. 1

FIG. 3

FIG. 2

FIG. 4

FIG. 1 is a front elevational view of a transparent conical beaker for drawing up laboratory samples, showing my new design;

FIG. 2 is a top plan view thereof;

FIG. 3 is a section taken on the line 3—3 of FIG. 2;
and

FIG. 4 is a bottom plan view of my new design.

I claim:

The ornamental design for a conical beaker for drawing up laboratory samples, as shown.
